Inventor

Edward F. Baum

UNITED STATES PATENT OFFICE.

EDWARD F. BAUM, OF WORMLEYSBURG, PENNSYLVANIA.

Mechanically-Operated Toy.

1,294,027.

Specification of Letters Patent. Patented Feb. 11, 1919.

Application filed August 25, 1917. Serial No. 189,200.

To all whom it may concern:

Be it known that I, EDWARD F. BAUM, a citizen of the United States, residing at Wormleysburg, in the county of Cumberland and State of Pennsylvania, have made new and useful Improvements in Mechanically-Operated Toys.

My invention relates to that class of toys representing an animal in form, preferably a frog or toad, propelled by a mechanical device which is actuated by a spring, and the purpose of my invention is to provide a toy of this description, simple and substantial in construction which will have a life like action when operated.

I attain the object of my invention by the device illustrated in the accompanying drawing in which—

Figure 1 is a perspective side view. Fig. 2 is a longitudinal cross sectional view. Fig. 3 is a longitudinal cross sectional view showing a modification of the same. Fig. 4 is a perspective side view showing the manner in which the toy is operated. Fig. 5 is a sectional plan view which more fully illustrates the arrangement of the mechanism and construction thereof.

Similar letters refer to similar parts throughout the several views.

In Fig. 1 A. is a shell of sheet metal or other suitable material shaped to represent the head, body and hind legs of a frog. b b are the front legs which are fastened to a rod c, which passes transversally through the shell A, from side to side and turns in the holes f f which act as bearings. e is a pin attached to the shell A. on the outside to arrest the rearward action of the legs b b and to hold them in the proper position when the toy is at rest.

In Fig. 2 a coil spring is shown securely attached to the rod c the other end of which is fastened in any suitable manner to the inner surface of the shell A. In Fig. 3 a spiral spring s is substituted for the coil spring s shown in the other views.

Inasmuch as it is obvious that the rod c and the legs b b may also be actuated by other types of springs, I do not wish to confine myself to any particular kind.

To operate a toy made in accordance with my invention, the shell A. is pressed downward as shown in Fig. 4 which forces the fore legs b b forward in a longitudinal direction, engaging and tightening the spring s 55 on the rod c. When the pressure is quickly removed the tension on the spring s is released and the legs b b are drawn rearward with such force that the entire toy is thrown upward and forward from its base for a 60 short distance alighting in a sitting posture simulating the jump or hop of a live frog. The operation can be repeated at will and when a stick, cane or rod is used to apply the pressure the "frog" or "toad" may be 65 propelled or "chased" for an indefinite distance affording unlimited amusement, especially for a child.

Having described the construction and operation of my invention I pray that Letters Patent may be granted to me for the same in accordance with the following claims.

1. In a mechanical toy the combination of a shell in the form of the head, body and 70 hind legs of a frog, a rod extending transversally through the shell from shoulder to shoulder and turning in a rotary direction in bearings therein, front legs attached to said rod and a spring reciprocating therewith for actuating the same.

2. In a mechanical toy the combination of a shell in the form of a head, body and hind legs of a toad, a rod extending transversally through the shell from shoulder to 85 shoulder and turning in a revolving direction in bearings therein, front legs attached to said rod, and a spring reciprocating therewith for actuating the same.

3. In a mechanical toy the combination 90 of the shell A, the front legs b b, the rod c, the bearings f f, the pin e and the spring s, substantially described.

EDWARD F. BAUM.
